DESIGN FOR A HAT

Mildred E. Weitz, New York, N. Y.

Application September 9, 1942, Serial No. 108,168

Term of patent 3½ years

To all whom it may concern:

Be it known that I, Mildred E. Weitz, a citizen of the United States of America, residing in New York city, county of New York, and State of New York, have invented a new, original, and ornamental Design for a Hat, of which the following is a specification, reference being had to the accompanying drawing, forming part thereof, wherein, showing the configuration of the component elements thereof.

I claim:

The ornamental design for a hat, substantially as shown.

MILDRED E. WEIZT.
